UNITED STATES PATENT OFFICE.

GEORGE HAND, OF LAUREL SPRINGS, NEW JERSEY.

AIRPLANE FOR NIGHT ADVERTISING.

Application filed May 22, 1926. Serial No. 110,871.

The principal object of the present invention is to provide an airplane for night advertising which shall be possessed of an outer wing curve and which shall be devoid of parasite or added resistance such as would be produced by lamps or other parts projecting beyond the wing covering and which affords convenient means for changing letters or other display while in the air. Another object of the invention is to provide not only for building new airplanes possessed of the desirable features above referred to but also for incorporating those desirable features into existing airplanes while at the same time improving the latter in regard to high lift characteristics of the wing. Generally stated, the invention may be said to comprise an airplane having a translucent wing covering, a bank of lamps arranged inside of the translucent wing covering, a duplicate bank of circuit controllers adapted to light all the lamps, letters or characters adapted to operate certain of said controllers selectively to light certain of said lamps in correspondence with the contour of the letters or characters, and circuit connections for the lamps and controllers. The invention also comprises the improvements to be presently described and finally claimed.

In the following description reference will be made to the accompanying drawings illustrating one embodiment of the invention and in which

Figure 1 is a diagrammatic view of the under face of an airplane illustrating a part of the bank of lamps with which the same is equipped.

Fig. 2 is a cross-sectional view drawn to an enlarged scale and illustrating features of the invention.

Fig. 3 is a perspective view illustrating a part of a bank of controllers for the bank of lamps.

Fig. 4 is a diagrammatic view illustrative of circuit connections.

Fig. 5 is a fragmentary sectional view taken on the line 5—5 of Fig. 2 and drawn to an enlarged scale, and

Fig. 6 is a fragmentary sectional view taken on the line 6—6 of Fig. 2 and drawn to an enlarged scale.

Referring to the drawings it so happens that the invention is illustrated in applica-

tion to a R. A. F. wing curve changing it to a high lift wing curve, but the invention is applicable to new airplanes. However, the invention will be described in connection with the drawings and from that description those skilled in the art will know how to embody it in new machines. There is a bank of lamps of which a part is shown at the left in Fig. 1 but the bank may be co-extensive with the wing. For the sake of description it may be said that the lamps can be considered as arranged at the intersections of equally spaced parallel lines crossing each other at right angles and the bank of lamps for description may be considered as divided into groups such as 1 and 2, each group adapted by selection of the lamps lighted to produce letters or like characters. Each lamp 3 may have an individual reflector 4. It is important that the lamps and reflectors be arranged inside of a transparent wing covering 5, shown in dotted lines in Fig. 2. This can well be accomplished by mounting the reflectors 4 in such a way as to cover openings through a sheet or support 6, shown in full lines in Fig. 2, extending from the cap strip to the rear edge of the wing and underlying the translucent wing covering 5. The reflectors 4 are arranged behind the openings in the support 6 and are supported by it. The transparent or translucent wing covering 5 overlies the openings in the support 6 and in the reflectors, Fig. 5, and by reference to Figs. 5 and 6, along with the other figures it is evident that the reflectors are spaced between the webs 7 and 8. The lamps 3 are carried by the reflectors. The support 6 may be carried by webs 7 aligned with the webs 8 which extend between the wing spars 9. There is a bank of circuit controllers and they are arranged at the intersections of the lines shown in Fig. 3 so that the arrangement of the controllers in the bank of controllers is a duplicate of the arrangement of the lamps. As shown each controller controls a single lamp. Letters such as shown in Fig. 3 when applied to the bank of circuit controllers operate those controllers with which they come in contact, thus causing the controllers to light the lamps which correspond in position with the controllers actuated by the letters thus reproducing in the bank of lamps the outline of the letters in lighted lamps. Referring to Fig. 4, 10 and 11 indicate circuit

controllers, or more accurately, contacts, and they are each connected to one side of lamps indicated at 12 and 13 by separate leads 14. The other side of the lamps may be connected to a return or ground conductor 15 which may well be the reflectors 4 and the sheet or support 6, to one side of the source or battery 16, the other side of which is connected by 17, strip 18 on panel 19, to the conducting letters 20, carried by switch plate 21 hinged to panel 19, through contacts 22, so that when the switch plate is closed the circuit paths through contacts 10 are completed lighting lamps 12, whereas since no contact is made at the contacts 11 because the letter 20 does not reach them, the lamps 13 remain dark. The device illustrated in Fig. 3 may well be located in the cockpit and while in flight the operator may change the display by employing a switch plate 21 having thereon letters appropriate for producing the changed display in the manner indicated. It is a small matter to apply any letters or characters to one or more switch plates in preparation for use during flight. In Fig. 1 the black crosses indicate lighted lamps and the circles indicate lamps that are unlighted so that if we consider Fig. 3 the circuit controllers corresponding to lighted lamps are closed by the letters as has been described.

Inasmuch as the lamps and reflectors are arranged inside of a translucent wing covering, it follows that they offer no resistance. The aviator or his assistant can readily turn on and off the display by simply manipulating the switch plate 21 which can be readily done while the machine is in flight. Similarly while the machine is in flight one switch plate 21 can be substituted for another thus changing the announcement or display.

The switch plate 21 and panel 19, may be of insulating material and the letters 20 may be backed with rubber as indicated in Fig. 4 to afford them some range of adjustment in respect to the circuit controllers 10 and 11.

The described advantages due to the arrangement of the luminous characters or lighted advertising devices inside of the outer surface of the wing covering and also the additional advantage of preserving the aero dynamic efficiency of the wing curve

intact without adding any outside resistance to the air can be attained with any type of illuminated characters or source of illumination.

It will be obvious to those skilled in the art to which the invention relates that modifications may be made in details of construction and arrangement and in matters of mere form without departing from the spirit of the invention which is not limited to such matters or otherwise than the prior art and the appended claims may require.

I claim:

1. An airplane having a bank of lamps and individual reflectors therefor, a support plate having openings behind which the reflectors are mounted, a bank of circuit controllers corresponding with the bank of lamps, a switch plate movable in respect to the bank of circuit controllers and provided with characters adapted to establish circuit paths through some of the lamps in correspondence with the contour of the characters, and circuit connections, said reflectors attached to the support plate.

2. An airplane having a bank of lamps and individual reflectors therefor, a support plate having individual openings behind which the reflectors are individually mounted, a translucent wing covering overlying the plate and openings and lamps and reflectors, a bank of circuit controllers individually corresponding with the individual lamps of the bank, a switch plate movable in respect to the bank of circuit controllers and provided with controller operating means adapted to establish circuit paths through any and all of the lamps in correspondence with the contour of said means, and circuit connections.

3. An airplane having a bank of lamps and individual reflectors therefor, a support plate having openings behind which the reflectors are mounted, a translucent wing covering overlying the plate and lamps and reflectors, a bank of circuit controllers corresponding with the bank of lamps, a switch plate removable in respect to the bank of circuit controllers and provided with letters adapted to establish circuit paths through some of the lamps in correspondence with the contour of the letters, and circuit connections.

GEORGE HAND.
